UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

DRIVING MECHANISM.

Application filed February 9, 1924. Serial No. 691,566.

This invention relates to new and useful improvements in driving mechanisms, and the objects of the invention are to provide a driving mechanism which is of simple and durable construction, is noiseless in operation, contains few parts, which can be easily assembled or disassembled, and which can be economically manufactured.

Further objects of the invention are to provide a driving mechanism having oppositely disposed members which are in operative engagement with an eccentrically mounted driving element and have rolling operative engagement with a reciprocating cross head for actuating the same.

Still further objects of the invention are to provide a mechanism for translating rotary motion into reciprocating motion in a simple and efficient manner, thereby reducing the cost of operation to minimum.

With these and other objects in view, my invention consists in certain novel features of construction and arrangement of parts, hereinafter more fully described and claimed and illustrated in the accompanying drawings, in which—

Figure 1 is a longitudinal cross section through a compressor provided with my improved driving mechanism.

Figure 2 is a horizontal cross section through the same.

Figure 3 is a perspective detail view of one of the rolling members.

Figure 4 is a vertical cross section through the same.

Figure 5 is a detail cross section illustrating the manner in which the wedge-shaped blocks forming bearings for said rolling members are adjustably mounted in the cross head.

Figure 6 is a detail view of the driving mechanism showing the eccentric member in its extreme left position.

Figure 7 is a similar view showing the position occupied by said driving mechanism when the eccentric mechanism is moved one-quarter turn.

Figure 8 is a similar view showing the eccentric occupying its extreme right position.

Figure 9 shows the eccentric occupying the third quarter of its cycle of operation.

Figure 10 shows a modified form of driving mechanism wherein instead of using rolling blocks a ring is utilized to transmit

motion from the eccentric to the sliding frame.

The driving mechanism disclosed in the present application and illustrated in the accompanying drawings is shown applied to a compressor or pump, but it is to be understood that the driving mechanism of my improved construction is equally as well adapted for various other purposes wherein it is desired to use reciprocating motion.

In the present instance, the mechanism is enclosed in a casing 10 which is hermetically sealed to prevent the escape of the circulating fluid and also to prevent leakage of the lubricating medium with which said casing is filled and in which the mechanism operates. A horizontally disposed shaft 11 is journaled in suitable bearings arranged in bosses 12 of said casing and said shaft is driven in any suitable manner, such as by a gear 14 fixed to said shaft and meshing with a pinion 15 which is arranged in the lower part of casing 10 and is fixed on a driven shaft 16 which extends into said casing through a suitable bearing 17. Shaft 16 may be connected to the motor or may be driven in any other suitable manner such as by a belt and pulley. An eccentric 18 is fixed to shaft 11, preferably by a key 18^a, and engaging the peripheral surface of said eccentric are the concave faces 19 of the inner ends of oppositely disposed blocks 20. The outer ends of said blocks are provided with convexed faces 21 which have a rolling bearing on the inwardly presented faces 22 of bearing blocks 24.

These bearing blocks rest against the end walls 25 of a reciprocating cross head 26 which is preferably box-shape in cross section, having top and bottom walls 27 and an outwardly presented side wall or flange 28. A centrally disposed opening 29 is formed in said side wall to provide access to the eccentric and the rolling blocks 20, as shown in Figure 1. A pair of oppositely disposed pistons 30 is fixed to the end walls 25 and project therefrom into oppositely disposed axially aligned cylinders 10^a carried by said casing 10.

In the drawings, a two-stage type of compressor is shown and pistons 30 are in telescopic engagement with cooperating pistons 31 which are detachably carried by a reciprocating cross head 32 which is similar in construction to cross head 26 having end

walls 34, top and bottom walls 35 and a side wall 36. Bearing blocks 37 bear against the end walls 34 and form bearings for the convex faces of the outer ends of rolling blocks 38, the concave faces of the inner ends of which are in engagement with an eccentric 39 which is fixed to shaft 11 in juxtaposed relation to eccentric 18. Eccentrics 18 and 39 are preferably arranged in oppositely disposed relation to each other in order to balance the pressure when the machine is in operation.

Bearing blocks 24 and 37 are preferably wedge-shaped so that by adjusting said blocks longitudinally in the proper direction, rolling members 20 and 38 may be mounted in proper operative contact with their respective eccentrics and bearing blocks. The adjustment of the bearing blocks is accomplished by means of adjusting screws 40 which are rotatably seated in the top and bottom walls of cross heads 24 and 32 and have their threaded ends screw-seated in threaded openings 41 formed in the ends of bearing blocks 24 and 37. Thus, by adjusting screws 40 in the proper direction said bearing blocks may be moved upwardly or downwardly, as desired.

In order to prevent displacement of said bearing blocks, the side walls 28 and 36 of their respective cross heads are provided with elongated slots 42 which are traversed by shanks of screws 44 carried by said bearing blocks and having their heads 45 bearing 35 against the side walls of the respective cross heads.

The wedge-shape of the bearing blocks is preferably obtained by forming the inner bearing faces of said blocks inclined from the perpendicular as shown in Figures 6 to 9, inclusive, and the rolling members are arranged at an angle to the longitudinal axis of the cross head, as shown by line $\alpha-\alpha$ in Figure 6, the angle of inclination being 45 toward the line of rotation of the eccentric. Thus the operating pressure is brought to bear against the bearing blocks at a point slightly in advance of the longitudinal axis of the cross head, thereby preventing slipping of the convex faces of the rolling members on the inclined faces of the bearing blocks and insuring at all times proper operative contact between said rolling members and their respective bearing blocks.

55 The rolling members are provided in their top and bottom edges adjacent to their outer ends with curved portions 46 which are adapted to be engaged by transversely curved lugs 47 projecting laterally and inwardly from the side faces of cross heads 26 and 32. These lugs serve to guide the blocks in their proper operative positions and prevent the accidental displacement thereof. The concave faces of rolling blocks 20 and 38 are channeled and the channels

so formed are filled with suitable metal, such as babbitt, as indicated at 47 in Figures 3 and 4. The bodies of the rolling members are provided with series of angularly disposed bores 48, vertically disposed bores 49, and horizontally disposed bores 50 which are then filled with babbitt. These bores preferably communicate with each other or with the channel and serve to convey away from the concave faces of said blocks and dissipate the heat generated by friction between the eccentrics and said concave faces.

In the modified form shown in Figure 10 an eccentric 51 instead of engaging oppositely disposed members, engages a ring 52 which has a rolling engagement with the adjustable track members or blocks carried by the sliding crosshead. While this construction effectively engages the blocks, it does not provide any means of take-up between the eccentric and the rolling member. My improved driving mechanism provides a quiet running mechanism by means of which the power is transmitted from the shaft to the reciprocating members in an even balanced manner so that all violent or sudden jars or motions are eliminated thereby prolonging the life of the parts and providing smooth running mechanism.

While I have shown and described the preferred form of my invention, it is obvious that various changes in the construction and arrangement of parts of my improved driving mechanism may be made and substituted for those herein shown and described without departing from the spirit of my invention.

I claim:

1. A driving mechanism comprising an eccentric, a pair of oppositely disposed members having concave inner ends for partially engaging the peripheral face of said eccentric and having convex outer ends disposed eccentrically to said inner ends, and reciprocating members having faces inclined from vertical engaged by the outer convex ends of said first mentioned members at points disposed on the opposite sides of the horizontal axis.

2. A driving mechanism comprising an eccentrically mounted element, a pair of oppositely disposed blocks having inner ends in engagement therewith and having convex outer ends disposed eccentrically to said inner ends, and reciprocating members having faces inclined from vertical and in rolling operative contact with said convex ends and operable by said blocks.

3. A driving mechanism comprising an eccentric, a pair of oppositely disposed blocks in engagement with said eccentric, a reciprocating box-shaped cross head having a rolling operative contact with the outer convex ends of said blocks and oper-

- able thereby, and means projecting laterally from the side wall of said cross head and engaging top and bottom faces of said blocks for retaining said blocks in position.
5. 4. A driving mechanism comprising in combination, a revoluble shaft, an eccentric fixed on said shaft, a pair of oppositely disposed members having their inner ends formed concave for engaging said eccentric and the outer ends convex, a reciprocating box-shaped cross head, and bearing blocks vertically disposed in said cross head and having their inner faces inclined from vertical and engaged by said members for actuating said cross head.
5. A driving mechanism comprising in combination, a shaft, an eccentric member fixed thereon, a pair of oppositely disposed rolling members having their inner ends in operative engagement with said eccentric and provided with convex outer ends, a slideable cross head, and bearing blocks in said cross head having their inner faces inclined from vertical in a predetermined relation to the line of travel of said eccentric and forming tracks for said convex ends of said members whereby the latter have rolling operative engagement therewith and operate said cross head.
30. 6. A driving mechanism comprising a shaft, a driving member eccentrically mounted thereon, a pair of oppositely disposed members having their inner ends in operative engagement with said eccentric member and provided with convex outer ends, a box-shaped slideable cross head, means extending laterally therefrom for engaging and retaining said rolling members in position, and bearing blocks adjustably arranged in said cross head and having inwardly presented inclined faces for forming rolling engagement with the convex ends of said members.
7. A driving mechanism comprising in combination, a shaft, an eccentric fixed thereon, a pair of oppositely disposed rolling members having their inner ends in operative engagement with said eccentric and provided with curved outer ends, a reciprocating cross head, bearing blocks rigidly held in said cross head adapted to form tracks inclined from vertical in a predetermined relation to the line of travel of said eccentric for receiving the convex ends of said rolling members, and means for adjusting said bearing blocks longitudinally so as to vary said tracks radially relative to said shaft to maintain said members in proper operative engagement.
8. In a driving mechanism, the combination with a shaft and a member eccentrically fixed thereon, of a reciprocating cross head provided at its ends with inwardly disposed track bearings having faces inclined from vertical, and a pair of opposed members angularly disposed relative to the line of travel of said cross head and having their inner ends in operative engagement with said eccentrically mounted member and having convex outer ends for forming rolling operative engagement with said track members at points disposed on opposite sides of the longitudinal axis of said cross head.
9. In a driving mechanism of the class described, a driving block having a concave face adapted to engage the peripheral face of an eccentric driving member, and a convex face adapted to form rolling engagement with a cross head member and having formed in its upper and lower faces suitable seats adapted to be engaged by retaining members of the cross head.
10. In a driving mechanism of the class described, a driving element having a concave face adapted to engage the peripheral face of an eccentric driving member, and a convex face adapted to enter into rolling engagement with a cross head member, said block being formed of non-metallic material and provided in its concave face with a channel and in its body portion with a plurality of bores communicating with said channel, said channel and bores being filled with suitable metal whereby the heat produced by the bearing surfaces of said driving element and said eccentric member is distributed through the body portion of said element.
11. A mechanism comprising in combination an eccentrically mounted actuating member, a pair of oppositely disposed elongated members having concave inner ends operatively engaging said eccentric member and provided with convex outer ends, a slideable crosshead, track members thereon and having their inner faces inclined from vertical for engaging said convex ends of said elongated members, whereby said crosshead is reciprocated, said elongated members being provided in their top and bottom edges with V-shaped notches, and means on said crosshead extending into said notches for engaging and retaining said elongated members in operative positions.
- In testimony whereof I hereunto affix my signature this 4th day of February, 1924.
- JOHN O. CARREY.
